UNITED STATES PATENT OFFICE.

EMIL E. NOVOTNY, OF LOGAN, PENNSYLVANIA, ASSIGNOR TO JOHN STOGDELL
STOKES, OF PHILADELPHIA, PENNSYLVANIA.

GAGE FOR MAKING PRINTING EQUIPMENT.

1,387,802.

Specification of Letters Patent. Patented Aug. 16, 1921.

Application filed September 27, 1919. Serial No. 326,768.

To all whom it may concern:

Be it known that I, EMIL E. NOVOTNY, a citizen of the United States, residing at Logan, in the county of Philadelphia and State of Pennsylvania, have invented new and useful Improvements in Gages for Making Printing Equipment, of which the following is a specification.

This invention relates to gages, and has particular application to devices of this character adapted especially for use in the printing art for marking printing plates and matrices.

The marking of a matrix or a printing plate may be done for various reasons, such for instance as to obtain a predetermined paper margin for the printed matter to insure accurate registration of the plate on a printing press, and to attain a proper and selected superimposition of colors and the like on multicolor printing. The invention herein pertains to the structure of the gage itself, and while the latter is particularly well adapted for use in the printing art as hereinafter briefly referred to, I wish it to be understood that it is not limited in its application to this purpose of gagging and marking printing plates or their matrices but may be employed in any connection wherein it may be found advantageous or desirable.

The invention consists in construction, combination and arrangement of parts set forth in and falling within the scope of the appended claims.

In the accompanying drawings:

Figure 1 is a perspective view of a portion of the type form, including a section of the printer's chase and showing the application of one form of my gage thereto.

Fig. 2, is a view in side elevation, showing one manner of employing the gage on the type form in connection with a micrometer, the chase being shown in section.

Fig. 3 is a fragmentary view of a matrix marked with my gage.

Fig. 4 is a top plan view of a modified form of gage showing the same clamped on a chase bar.

Fig. 5 is a side view of the gage shown in Fig. 4, the chase bar being shown in the section.

Fig. 6 is a vertical, cross-sectional view taken through the gage shown in Fig. 5,

approximately centrally thereof and looking toward the marking flanges.

I will now proceed to describe my invention as used in conjunction with a body of type locked in a chase, as will be understood by reference to Fig. 2. From this type body we may assume that a matrix is to be molded so that it may be marked by the gage, during molding, with certain indications such as lines or scorings which are predetermined distances from the type forming portion of the molding face of such matrix as shown in Fig. 3. For the sake of illustration we may assume that it is desired to mold or cast from such a matrix a printing plate wherein a marginal edge of one inch will exist between the type and the edge of the plate. The type body shown at A is locked up in the usual chase indicated at B. At the time of locking the type body in the chase I also apply my gage thereto. In the form shown in Figs. 1 and 2 this gage embodies a U-shaped base or frame 1, which is adapted to span a bar of the chase, preferably adjacent one corner of the latter as shown in Fig. 1. This frame 1, may be of any suitable material, such as metal, and being wider than the chase bar may be rigidly fastened thereto in any convenient manner, such as by the insertion of furniture 2, between the inner legs 3, of the frame and the inner face of the chase bar, and by a set screw 4, which is threaded in the outer leg 5, of the frame and which bears against the outer edge of the chase bar. The top face of this frame is grooved longitudinally as at 6, for the reception of a tongue 7, formed on the underface of the slide gage plate 8, so that while this plate may have a sliding or shifting movement upon or relative to the top of the frame, it is incapable of a lateral or sidewise play or movement. This sliding plate is formed with slots 9, through which project set screws 10, for the purpose of locking the sliding plate against movement on the frame in any selected position of adjustment, as will be readily understood. While I have herein shown a pair of slots 9, and a pair of set screws 10, if desired, but one may be employed, or any equivalent arrangement may be resorted to for the purpose. The inner transverse edge of this sliding plate 8 is provided with an upturned

beveled flange 11, the knife edge 12 of which is intended to mark or score the material of the matrix or plate C of Fig. 3 to form the mark or indication *a* for the paper margin 5 as hereinafter described. Also formed on the top face of the plate 8, and extending parallel with but spaced apart from the flange 11, is a similar flange 13, the knife edge 14, of which will also mark or score 10 the material of the plate or matrix C with a line *b* parallel to that made by the edge 12 of the flange 11, and the line or score so left by knife edge 14 may be used as a guide in trimming off the plate or matrix if desired. 15

In employing the gage the latter is clamped or fastened on the chase as shown in Figs. 1 and 2 and if it is desired to have a certain margin between the type matter 20 of the matrix and the paper margin line *a* of such matrix, say one inch, a micrometer such as is shown at M is employed, the anvil of the micrometer shown at 15 being placed against the selected type, border or 25 rule of the body of type as shown in Fig. 2, and the slide 16 of the micrometer is then adjusted to the desired dimension, in the present instance, one inch, the slide being moved that distance from the anvil at the 30 end of the micrometer scale or shaft. The sliding plate 8 is then shifted or adjusted until the paper margin flange 13 abuts the depending tongue of the micrometer slide so that the distance between this flange 13 of 35 the plate 8 of the gage and the selected type, border or rule will be one inch. The screws 10 may now be tightened to clamp the sliding plate rigid with the base or frame thereof. The chase with the type body locked 40 therein and the adjusted gage clamped in position with its flange 11 one inch from the type may now be employed for the making of the matrix partially shown in Fig. 3. For instance, should the chase with the gage 45 thereon as just described be placed in a press and a sheet of material, such as a plastic material placed on top of the type and chase, and subjected to pressure, in addition to the type being reproduced in the 50 face of the sheet, the score mark *a* will be reproduced by the knife edge 12 of the flange 11, which mark will be one inch from the type impression T, and the second score mark *b* made by the knife edge 14 of the 55 flange 13 will be reproduced in the sheet of material, parallel with but spaced from the score or mark *a*. When the sheet has been trimmed along the outer score or score mark *b*, the material *d* lying between such 60 trimmed edge and the mark *a* may constitute a clamping margin which may lie beneath a clamping member when the matrix is placed in the casting box or other apparatus for casting plates from the matrix. 65

Of course, if desired I may provide the

sliding gage plate 8 with but one knife edged flange for scoring or marking purposes, as under many circumstances but a single score line or indication would be sufficient. 70

In Figs. 4 to 6 inclusive, I have shown a slightly modified form of the invention, in this instance it not being necessary to employ the separate micrometer M as is shown and described in Fig. 2. Referring 75 to said Figs. 4 to 6 inclusive, the U-shaped base or frame 17 of the gage has one side edge thereof divided into a scale 18 running from 0 to 12, the divisions of the scale representing picas, there of course being 6 picas 80 to the inch which is a standard printer's measure. Slidably mounted on the top of the frame 17 is a plate 19 having an elongated slot 20, and set screw 21, by means of which the plate may be held in any selected position of adjustment relative to the top. This plate 19 is also provided with a tongue 22, seating in the groove 23, in the top of the frame 17. A second elongated slot 24, is formed in the plate and through 90 this slot projects a shank 25 of a T shaped block 26, the head of the latter seating in a groove 27, formed in the top wall of the frame 17. The head of the block 26 is threaded onto the screw shank of the 95 micrometer screw 29, the head 30 of the latter being marked circumferentially with a scale 31, the divisions of which indicate points of which there are twelve to the pica, so that one complete revolution of the micrometer screw is equivalent to one pica. A small spring pointer 32 is fastened at one end to the frame 17, and its opposite end or point seats in grooves 31' constituting the indicating lines of the scale 31 and thus this pointer will positively aline with the selected division of the scale. The micrometer screw 29 is held against longitudinal movement by annular flanges 33, so that with the rotation of the micrometer screw the block 26 threaded thereon will be caused to travel in its slot. The side edge of the sliding plate 19, adjacent the scale 18 of the frame is provided with a row of bores or holes 34, the centers of which aline with the division lines 115 or marks of this pica scale 18. An alining pin is intended to selectively seat in the holes 34, the shank end of this alining pin also seating in the socket 36 formed in the side of the block-shank 25. 120

The manner of employing this form of gage will be readily understood. Referring to Figs. 4 and 5, if it is desired to shift the plate 19 on the frame 17 a distance equal to a number of picas the alining pin 35 is withdrawn and the plate is shifted with the hand until the hole or aperture 34 indicating that particular pica, considered from the zero mark, is brought into alinement with the zero mark on the scale 18 of the frame 17. 130

The pin may then be thrust back or socketed in the shank 25 of the block, being of course inserted in the hole which at that time has been brought into alinement with 5 the socket of the block. If, however, it is desired to shift the sliding plate 19, relative to its frame 17, a smaller distance than one complete pica, as where it may be desired to obtain a dimension of picas and 10 points, or parts of a pica, then it is only necessary to turn the disk 30, constituting the head of the micrometer screw 29 until the scale 31 in conjunction with the pointer 32 indicates that the sliding plate has received 15 the desired degree of movement. Of course this rotation of the micrometer screw will cause the block to feed along the screw the selected distance, carrying with it the plate 19 which is connected with the 20 block at this time by the alining pin 35. It will thus be seen that relatively large or rough dimensions or degrees of movement of the plate relative to the frame may be obtained by simply pulling out the alining 25 pin 35 and shifting the plate bodily with the hand, again inserting the pin after the plate has been moved to the desired extent. But where fine dimensions or minute degrees of movement are required, for instance 30 less than a full pica, then the micrometer screw may be resorted to and this screw will not only shift the plate but will indicate clearly, by means of the pointer and the scale on the disk of the micrometer screw, 35 when the plate has been shifted to the proper degree. Of course this sliding plate 19 is provided with the marking flanges, in the present instance shown at 12' and 14' these flanges performing the same functions for 40 those described for the structure shown in Figs. 1 and 2.

I have herein merely briefly outlined a particular purpose for which my invention may be used, but obviously it may be employed 45 as a marking gage under any condition where its employment will be found advantageous.

While I have herein shown and described certain preferred embodiments of my invention, I wish it to be understood that I do not limit myself to all the precise details of construction set forth by way of illustration, as modification and variation may be made without departing from the spirit of the 50 invention or exceeding the scope of the appended claims.

What I claim is:

1. A gage comprising a base, means for clamping the base to a suitable support, a 55 sliding member adjustably mounted on the base, means for fastening the member on the base in a selected position, and a marking element projecting from the plate.

2. A gage comprising an approximately 60 U-shaped clamp-like base, a plate mounted

to slide on the base, means for fastening the plate in a selected position of adjustment on the base, and a pair of spaced parallel marking elements projecting from the plate.

3. A gage comprising a clamp-like base, 70 means for fastening the base upon a suitable support, a plate mounted for adjustment on the base, and a marking flange projecting from the plate and extending transversely of the face of the latter and provided 75 with a marking edge.

4. A gage comprising a base adapted to be clamped upon a support, a plate slidably mounted on the base and provided with a slot and having a marking element which 80 projects from a face of the plate, and a set screw having a shank portion projecting through the slot and engaging in the base for fastening the plate in a selected position of adjustment relative to the base. 85

5. A gage comprising a base adapted to be clamped upon a support, a plate slidably mounted on the base and provided with a slot and having a marking element which projects from a face of the plate, said base 90 having a scale thereon and said plate also having indications corresponding to the scale of the base, and means for fastening the plate in an adjusted position determined by the relative position of the scale and the 95 indications of the plate.

6. A gage comprising a base member and a shiftable member carried thereby, said shiftable member having a marking element, there being a pica scale on the base and indications on the shiftable member corresponding to the pica scale, and a screw member for shifting the shiftable member, the screw member having a point scale for determining the degree of movement to be imparted to the shiftable member. 100

7. The combination with a clamping base having a scale thereon, of a shiftable member provided with a marking element and movable relative to the base to the position 110 predetermined on the scale, and mechanism for imparting a further shifting movement to the shiftable member.

8. The combination with a clamping base, of a shiftable member carried thereby and 115 provided with a marking device, and mechanism, including a screw member provided with a scale, for moving the shiftable member a selected distance on the base.

9. The combination with a clamping base, 120 of a shiftable member mounted thereon and provided with a marking device, a screw member adapted to be rotated to move the shiftable member relative to the base, the screw member being provided with a scale. 125

10. The combination with a clamping base having a scale thereon, of a shiftable member having a marking element, means for locking the shiftable member in a predetermined position relative to the scale of 130

the base, and mechanism provided with a scale for also imparting movement to the shiftable member.

11. The combination with a base provided with a scale, of a sliding member mounted on the base and having a marking element, said member having a series of spaced openings adapted to align with the divisions of the scale of the base, an alining pin adapted to selectively seat in said openings, a member on the base in which said alining pin is adapted to socket, mechanism engaging said last mentioned member for imparting movement thereto, said mechanism being provided with a scale.

12. A gage for placing position indicating marks on matrices and the like, comprising a base adapted to be clamped to a member of a type chase, a member slidably mounted on the base and having a part

adapted to extend into proximity to a type body located in the chase, said part being provided with a marking element adapted to impress a position indicating mark on a matrix pressed upon the type body, and means for securing said member in adjusted position on the base.

13. A gage for marking matrices and the like, including a clamping base, a member slidably mounted on the base and provided with a marking element, a block slidably mounted in the base, means for connecting the sliding member in different positions to the block, a screw engaging the block to give fine adjustments, and means for indicating the positioning of the screw in relation to the base.

In testimony whereof I have hereunto set my hand.

EMIL E. NOVOTNY.
